UNITED STATES PATENT OFFICE.

LOUIS OUDESLUYS, OF BALTIMORE, MARYLAND.

DESIGN FOR A BADGE.

SPECIFICATION forming part of Design No. 22,239, dated February 28, 1893.

Application filed December 15, 1892. Serial No. 455,309. Term of patent 3½ years.

To all whom it may concern:

Be it known that I, LOUIS OUDESLUYS, a citizen of the United States, residing at Baltimore city, in the State of Maryland, have 5 invented a certain new and useful Improvement in an Improved Design for Badges, of which the following is a specification.

My design relates to a badge, which consists of a head, in relief, and designed to represent a full-face view of the head of Columbus. Suspended from, or integral with the head is a cross-bar, the front surface of which is designed to be ornamented and inscribed with any desired lettering or figuring. A ribbon or streamer is pendent from the said bar, and is designed to be ornamented in various colors.

The accompanying drawing illustrates the design, in which

The letter, A, represents the bar located below the head, B. Suspended from the bar, A, is the streamer, C, having the notch, α , therein.

The head a full-faced view of Columbus, the bar, and the streamer, are the essential features of the design.

Having thus described my design, I claim—

The design of a badge, substantially as described and shown.

In testimony whereof I affix my signature in the presence of two witnesses.

LOUIS OUDESLUYS.

Witnesses:

F. PARKER DAVIS,
JNO. T. MADDOX.
